TRANSFORMER CASE

Buell Moore, Houston, Tex., assignor to Esquire, Inc.,
New York, N.Y., a corporation of Delaware

Filed Dec. 10, 1962, Ser. No. 72,777

Term of patent 14 years

(Cl. D26—15)

Fig. 2

FIG. 1 is a perspective view of the front, top and one side of a transformer case embodying my new design; and

FIG. 2 is a perspective view of the back, bottom and other side of the case of FIG. 1.

I claim:

The ornamental design for a transformer case, substantially as shown.
